US0D1070808S

(12) **United States Design Patent** (10) **Patent No.:** **US D1,070,808 S**
(45) **Date of Patent:** **** Apr. 15, 2025**

(54) **AIR PURIFIER HEADPHONES**

- (71) Applicant: **Dyson Technology Limited**,
Malmesbury (GB)
- (72) Inventors: **Mark Joseph Staniforth**, Bristol (GB);
Hannah Jayne Jobling Hersey,
Newcastle (GB); **Simon Brian**
McNamee, Bristol (GB); **Howard**
Shi-How Cheng, Swindon (GB); **Ben**
Lowson, Durham (GB)
- (73) Assignee: **Dyson Technology Limited**,
Malmesbury (GB)

(**) Term: **15 Years**

(21) Appl. No.: **29/941,443**

(22) Filed: **May 9, 2024**

Related U.S. Application Data

- (63) Continuation of application No. 29/839,499, filed on
May 20, 2022, now Pat. No. Des. 1,042,396.

(30) **Foreign Application Priority Data**

Nov. 23, 2021 (EM) 001483788-0001

- (51) **LOC (15) Cl.** **14-01**

(57) **CLAIM**

The ornamental design for air purifier headphones as shown and described.

DESCRIPTION

FIG. 1 is a perspective view of an air purifier headphones.

FIG. 2 is a top view thereof.

FIG. 3 is a left side view thereof.

FIG. 4 is a rear view thereof.

FIG. 5 is a right side view thereof.

FIG. 6 is a front view thereof.

FIG. 7 is a bottom view thereof.

FIG. 8 is a perspective view of another air purifier headphones.

FIG. 9 is a top view thereof.

FIG. 10 is a left side view thereof.

FIG. 11 is a rear view thereof.

FIG. 12 is a right side view thereof.

FIG. 13 is a front view thereof; and,

FIG. 14 is a bottom view thereof.

The broken lines illustrate portions of the air purifier headphones that form no part of the claimed design.
